UNITED STATES PATENT OFFICE.

CHARLES HUSCHER, OF GOLDEN, COLORADO.

ERASER-SUPPORTING MEANS FOR TYPEWRITERS.

Application filed February 11, 1922. Serial No. 535,736.

To all whom it may concern:

Be it known that I, CHARLES HUSCHER, a citizen of the United States, residing at Golden, County of Jefferson, and State of Colorado, have invented certain new and useful Improvements in Eraser-Supporting Means for Typewriters; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to means to be applied to a typewriter for the purpose of conveniently supporting an eraser thereon.

It is well known that more or less trouble is always experienced by the typewriter operators, due to the fact that the eraser becomes misplaced and is hard to find.

It is the object of this invention to provide a device that is of simple and cheap construction and which can be readily attached to the framework of a typewriter, and which is provided with means for supporting the ordinary typewriter eraser.

In order to more clearly describe my invention, I shall have reference to the accompanying drawing in which—

Fig. 1 is a side elevation of a typewriter with my supporting means applied thereto;

Fig. 2 is a side elevation of one embodiment of my invention;

Fig. 3 is an end view of the same with the eraser omitted;

Fig. 4 is a side elevation of a modified form of my invention; and

Fig. 5 is an end elevation thereof with the eraser omitted.

The same reference characters will be used to indicate the same parts throughout the several views.

Numeral 1 represents the framework of a typewriter to which my eraser supporter 2 is attached. My supporting means consists of a member 3 of thin flexible material whose upper and lower ends 4 and 5 respec-

tively are curved in the manner shown in Figs. 3 and 5. To the side of member 3 I attach by suitable means a box-like receptacle 6 having a rear wall 7, bottom 8, and an upwardly extending portion 9 in the front. Members 6 and 3 form a receptacle within which the eraser 10 may be placed. The supporting means is attached to the framework 1 in the manner shown in Figs. 1, 4 and 5, that is, by bending the ends 4 and 5 about the top and the bottom of the frame 1.

In Figs. 4 and 5 I have shown a modified form in which the member 6 is replaced by a pair of arms 11, which are cut from the material of the plate 3 and bent outwardly therefrom and then parallel therewith. At the bottom of plate 3 I provide another arm 12 which is bent outwardly at right angles to the plate 3 and then upwardly. Arms 11 and 12 form means for holding the eraser in the manner indicated.

I am aware that other specific forms of construction may be employed, and I do not wish to be restricted to the embodiments shown, but reserve the right to change my device within the scope of the appended claims.

Having now described my invention, what I claim is—

1. An eraser support adapted to hold a circular eraser and adapted to be attached to the framework of a typewriter, consisting of a member of flexible material having its opposite ends bent into the form of hooks whereby it may be attached and held in place on a typewriter frame, and means for holding an eraser, comprising a pocket formed on the outside of said member and adapted to engage the outside of the eraser and spaced points on the periphery thereof.

2. An eraser support adapted to hold a circular eraser and adapted to be attached to the framework of a typewriter, consisting of a member of flexible material having its opposite ends bent into the form of hooks whereby it may be attached and held in place on a typewriter frame, and means for holding an eraser, comprising a pocket

formed on the outside of said member, said pocket being secured to the member along three adjacent sides.

3. An eraser support adapted to hold a circular eraser and adapted to be attached to the framework of a typewriter, consisting of a member of flexible material having its opposite ends bent into the form of hooks

whereby it may be attached and held in place on a typewriter frame, and means for holding an eraser, comprising portions extending outwardly from said member and means extending substantially parallel with said member and spaced therefrom.

In testimony whereof I affix my signature.

CHARLES HUSCHER.
